UNITED STATES PATENT OFFICE.

JOSEPH E. KENNEDY, OF NEW YORK, N. Y.

DISINTEGRATING OR PULVERIZING APPARATUS.

Application filed October 16, 1922. Serial No. 594,698.

This invention relates to apparatus for disintegrating or pulverizing material such as coal, lignite, ore, rock, bone, etc., and relates particularly to apparatus of this character commercially known as "grinding mills" in which a revolvably supported tubular or cylindrical drum has grinding means therein operable during the revolving of the drum to disintegrate and pulverize the material, and it is the principal object of the invention to connect a disintegrating or pulverizing drum of this character in circulation with suction means to draw disintegrated or pulverized material from the drum and deliver the same to a receiver connected in circuit with the suction means and the drum at the delivery side of the suction means, to arrange in the connection of the suction means and receiver means to separate coarse particles or unpulverized material from the material delivered by the suction means and return the same to the pulverizing drum and to provide regulable means to control the influx of air to and the efflux of air from the drum and thereby the constant delivery of disintegrated material of predetermined uniform finenesses.

It is another object of the invention to provide an apparatus of this character wherein freely moving grinding elements are contained within a drum and the latter having charging and delivery openings at opposite ends of an improved construction and arrangement of drum to prevent the delivery through the drum openings of material being ground or the grinding elements by the cascading movement thereof during the revolving of the drum by arranging the openings of the drum at such an angle relative to the axis of the drum whereby material entering said openings from the drum is re-entered into the drum.

It is a further object of the invention to provide an apparatus of this character in which a cylindrical drum having grinding elements therein and arranged with charging and delivery openings at opposite ends is connected in circulation with pneumatic or suction delivery means for the disintegrated material, of means to deliver material to the drum without impairing the action of the suction or pneumatic means.

Another object of my invention relates to an improved construction and arrangement of adjustable separator for connection in the delivery of the suction means whereby to

separate material of varying degrees of fineness from the material delivered by the suction means from the grinding drum.

It is a further object of the invention to provide a pulverizing apparatus in which a grinding drum is connected in circuit with pneumatic or suction means to arrange in the circuit with the suction or pneumatic means at the delivery side thereof, means to reduce the force of the air delivered by the suction means in successive steps to separate material from the air in varying degrees of fineness at said successive steps in the reduction of the air force.

Other objects and advantages will hereinafter appear.

In the drawings accompanying and forming a part of this specification, Figure 1 is a rear elevation of disintegrating or pulverizing apparatus illustrating in a diagrammatic manner an installation of pulverizing apparatus embodying my invention.

Figure 2 is a sectional side elevation on an enlarged scale relative to Figure 1 showing my improved arrangement of drum together with the connection thereof in circulation with suction or pneumatic means and the means to feed material to the drum without impairing the action of the suction or pneumatic means.

Figure 3 is a plan view looking at the top of Figure 2.

Figure 4 is a side elevation, partly in section, of my improved adjustable separator whereby to separate material of varying degrees of fineness from the air delivered by the suction means from the drum.

Figure 5 is a view looking at the top of Figure 4; and

Figures 6 and 7 are plan and front elevational views respectively illustrating in a diagrammatic manner a modified installation of my improved means and method of reducing the force of the air delivered by the suction means at successive stages or steps and delivering the material at one of said steps of a different fineness than at the other steps.

Similar characters of reference designate like parts throughout the different views of the drawings.

The embodiment of my invention shown in the drawings comprises a tubular or cylindrical drum D having hollow trunnions 4, 5 at opposite ends and axially of the drum whereby the drum is revolvably supported in

bearings in pillow blocks 6, 7 mounted upon a suitable base B, shown in the present instance as a concrete base. The trunnion 4 serves as a feeding opening for the drum 5 while the trunnion 5 is the delivery outlet for disintegrated or pulverized material. The drum is driven in a suitable manner as by an annular gear 8 mounted upon the drum meshing with a pinion 8' fixed to a shaft 9' driven from a suitable source of power by a belt passing around a pulley P. Drums in apparatus of this character are of large size and great weight particularly when loaded with grinding elements and the material to be ground. Heretofore to provide large bearing surfaces for the trunnion supports to compensate for wear and obviate the necessity of reducing the capacity of the drum the supporting trunnions were made of considerable length necessitating means on the interior of the feeding trunnion operative to deliver material therethrough to the drum during the revolution of the latter. In commercial mills of this character the disintegrated material is discharged through the delivery trunnion means being provided in the drum to lift the material from below to above the axis of the drum and direct the elevated material to such trunnion with means arranged in the trunnion to convey the material therethrough. To obviate the necessity of arranging conveying means in the trunnions to charge material to and deliver pulverized material from the drum and also provide large bearing surfaces the trunnions 4, 5 are made of large diameter relative to the size of the drum. These trunnions are constructed integral with the ends or heads of the drum which are of cast material, and in order to keep down the weight of the casting the walls of the trunnions are made relatively thin with the walls of the openings preferably inclining or flaring outward from the drum.

To reduce the size of the openings in the trunnions and to maintain the capacity of the drum in the use of the large trunnions as above set forth, reducers in the form of annular members to engage within the trunnion openings are provided, said reducers being arranged with a wall extending at an angle to the axis of the drum to re-enter material entering said openings into the drum. In the present instance these members comprise an annular plate portion 9 whereby they are detachably connected at the peripheral portion to the ends of the trunnions and the openings in said plates are of reduced size relative to the openings in the trunnions, an annular web 10 extending and diverging inwardly toward the drum from the opening of said plate portion with the diameter of such webs at the inner end substantially the same as the diameter of the

trunnion opening at the inner end as clearly shown in Figure 2. Grinding means within the drum operates through the movement of the drum to have movement imparted thereto relative to the drum to grind or pulverize material in the drum and consists of freely moving elements, shown in the present instance as metallic balls. By the arrangement of the reducers for the trunnion openings as the drum is revolved and the grinding elements as well as the material being ground cascades in the drum any of the grinding elements or material which enters the openings in said reducers is directed back into the drum.

To deliver disintegrated or pulverized material from the drum it is connected in substantially airtight circulation with pneumatic or suction means operative to draw air from and through the drum and therewith the pulverized material. This pneumatic means comprises a rotary suction fan (designated in a general way by F) the operative element of which is driven by a belt (not shown) from a suitable source of power 90 passed around a pulley 11 mounted on a shaft 12, carrying the operative fan element, journaled in bearing members 13 mounted upon the base B.

The intake of the fan is connected to the delivery outlet of the pulverizing drum D through a receptacle or casing 14 mounted upon the base B, the fan being connected thereto, as at 15, in alinement with the axis of the drum, the latter having a substantially air-tight connection with the receptacle. For this purpose the plate 9 of the reducer in the delivery trunnion 5 has an axial cylindrical extension 16 having a sliding joint connection with a flange 17 extending around the inlet of the casing 14, said joint consisting of a flanged sleeve or collar 18 engaging the flange 17 of the receptacle 14 slidably mounted on the sleeve 16 of the trunnion reducer and connected to headed pins or bolts 20 slidably engaging in openings in lugs 21 extending laterally from the sleeve 16, said collar being urged outward against the flange 17 by springs 22 coiled about the pins 20 and confined between the lugs 21 and the sleeve.

The delivery of the fan has a pipe 23 leading therefrom for the delivery of pulverized or comminuted material drawn from the drum to a separator (designated in a general way by S), said pipe being connected to said separator adjacent the top. The force of the air laden with the material drawn off from the drum is somewhat reduced as it enters the separator S whereby any particles or coarse material drawn off from the mill and delivered by the fan to the separator will drop or gravitate to the bottom of the separator, which bottom is preferably arranged with converging walls and

having an outlet to which a pipe 24 is connected to deliver such particles or coarse material to the charging opening of the drum in a manner as hereinafter set forth.

5 The separator S has a pipe 25 leading from the top to a closed receiver hopper 26 for the collection of the pulverized or powdered material carried by the air, and connected preferably adjacent the top thereof.

10 This receiver has an outlet with a closure in a converging bottom superposed to a bin or bins 27 to which material is delivered from the receiver. To deliver material to either of said bins an adjustable chute 19 is connected to the outlet of the receiver 26. The receiver is connected by a pipe 28 leading from the top to the charging trunnion of the drum through a receptacle or casing 29 mounted upon the base B and having a substantially air-tight connection with the charging trunnion of the drum in a manner similar to the connection of the receptacle 14 with the delivery trunnion of the drum, and consists of a sleeve or collar 30 slidably mounted on an axial tubular extension 32 of the plate portion 9 of the trunnion reducer of the charging opening of the drum and connected to headed pins or bolts 33 slidably engaging in openings in lugs or ears 34 extending laterally from the reducer extension 32 and urged outward by springs 35 coiled about the pins 33 and confined between the lugs 34 and the sleeve 30. The sleeve or collar 30 has a rubbing contact with flange 36 extending around the outlet of the receptacle 29. The receiver 26 being of relatively large size the force of the air delivered thereto is materially decreased with the result that the pulverized material carried by the air in the form of dust settles in the receiver while the freed air passes out through the outlet pipe 28 and re-entered into the drum by the suction of the fan and under certain conditions is re-entered into the drum by the force of the air delivered by the fan, where it acts, due to the flaring wall 10 of the reducer in the trunnion openings, to create an agitation of the air within the drum which causes the air to more readily take up the pulverized material in the drum and the air in such condition is again withdrawn from the drum through the delivery opening by the fan. The pipe 24 leading from the bottom of the separator S is arranged to deliver the material separated from the air in separator slack to be again subjected to the grinding means in the drum, in the present instance connected to a chute 31 leading from a bin for the material to be ground to means to charge material to the drum as hereinafter described.

To charge the drum with material to be disintegrated a charging chute 37 extends through the receptacle 29 and has an inlet 38 to which the chute 31 is connected, the

material gravitating through the chute 31 and to the chute 37 maintaining the latter closed in the operation of the apparatus. The material is positively fed through the chute 37 by a plunger 41 slidably mounted in a cylindrical portion of the chute 37 extending beyond the connection thereof with the chute 31 to progressively advance the material along the chute 37. The plunger 41 is reciprocated by an eccentric 42 on a shaft 43 connected to the plunger by a rod 44, the shaft being connected to a source of power by a belt passing around a pulley 45. For the purpose of supplying additional air to the drum and to also reduce the force of suction of the air from the receiver 26 through the pipe 28 to the drum with the possibility of drawing air from the receiver which has not been entirely freed of pulverized material, means are provided to connect the charging opening of the drum to the surrounding atmosphere and to control said connection. For this purpose the receptacle 29 is arranged with one or more openings the area of which openings is regulated to control the influx of air into the drum, or entirely closed, by an adjustable closure, as at 46, shown in the form of gates slidably mounted upon the receptacle. By the adjusting of the closure to open the charging opening of the drum to the atmosphere the degree of fineness of the material drawn by the suction means from the drum may be controlled. The volume of air rushing through said opening or openings into the charging opening of the drum through the action of the suction means serves to agitate the air within the drum, which during the cascading of the material in the drum as the latter is rotated will facilitate the assimilating or taking up of disintegrated material of varying fineness depending upon the size of the opening to the atmosphere and the volume and velocity of air entering the drum.

The connection of the fan with the delivery opening of the drum is also arranged to be connected to the surrounding atmosphere in order to regulate and control the suction through or from the drum. For this purpose the receptacle 14 is arranged with one or more openings in the front and rear walls the areas of which are regulable by adjustable closures, as shown at 47, said closures being in the form of gates slidably mounted upon the receptacle wall. By opening either one or more of the closures to a greater or less extent the force of the suction from the drum is decreased and increased without impairing the delivery of the suction means. By entirely closing the openings the suction will be greater and coarser material will consequently be drawn off from the drum and delivered by the suction means, while if the opening or open-

- ings are partially or entirely open only material pulverized to an impalpably fine state will be drawn from the drum. Furthermore, by the arrangement of the regulable 5 openings in the connections of the suction means with the delivery and charging openings of the drum the suction means may serve as a means to draw or exhaust air from the delivery opening of the drum and 10 deliver the air under pressure to the charging opening, or the force of the suction from the drum may be decreased and increased without affecting the delivery of the air to the drum.
- 15 While it is not absolutely essential to the efficient operation of the apparatus the drum is preferably arranged with one or more transverse partitions to separate the drum into two or more chambers and in 20 which the material is delivered from one chamber to a successive chamber in a varying degree of fineness. In the present instance the drum is arranged with a single partition 48 separating the drum into two 25 chambers 49, 50, the chamber 49 containing grinding elements or balls of somewhat larger size than the grinding elements in chamber 50. The material is preliminarily ground or disintegrated in the chamber 49 and the particles of material when ground to a certain fineness will pass through perforations 52 circumferentially arranged in the partition into the chamber 50, the walls of the perforations diverging from the 30 chamber 49 to the chamber 50, whereby the clogging of said perforations by the material is prevented. The partition is arranged with a central enlarged opening 53 in line with the charging and delivery openings of 35 the drum to provide a clear passage through the drum for the sweep of the air by the suction means, and whereby any material which may be reduced to a pulverized state in the chamber 49 is drawn off from said 40 chamber by the suction means. To prevent the grinding elements from passing from one chamber into the other in the cascading movement thereof during the revolving of the drum the partition is arranged with a 45 deflecting surface, as at 54, which operates to direct the grinding elements in the chamber 50 away from the opening in the partition. To direct the grinding elements in chamber 50 from the opening a deflector is 50 arranged around said opening, as shown at 55.
- To facilitate the feeding of the grinding elements to the chamber 50 a tubular chute 56 is arranged in the receptacle 14, 60 said chute having an open end extending through the top of said receptacle with a removable closure, as at 40, and inclining downwardly through the delivery opening of the drum with the outlet opening into the drum. The grinding means may be fed

to the chamber 49 through an air inlet opening 46 in the chamber 29 to the charging chute 37 from which they are delivered into the chamber 49.

To further control the delivery of pulverized material of a predetermined fineness regulable means are arranged in the separator S, this separator being in the nature of what is commonly termed a "Cyclone separator", the connection of the pipe 23 therewith leading from the suction fan being substantially tangential to the peripheral wall of said chamber adjacent the top and above the converging bottom wall with the outlet pipe leading centrally from the top. To separate material of varying degrees of fineness from the material carried by the air in its passage through said separator the outlet pipe 25 has a tubular extension 57 adjustably connected thereto to extend into the separator chamber and adapted to have adjustment into and out from the pipe 25. This outlet pipe extension 57 is adjustably mounted to have telescoping movement into the pipe 25 by rods 58 circumferentially disposed around the pipe and secured at one end to angle brackets 59, said rods passing up through the top wall of the separator and having nuts 60 threaded thereon at the outside and resting upon the top of the separator as clearly shown in Figure 4. It will be obvious that by adjusting the nuts on the pipe supporting rods that the pipe extension may extend into the separator variable distances. The air in its passage through the separator must pass around the pipe extension, down into the separator chamber and then up through the outlet pipe, and the extent to which the pipe extension extends into the separator chamber will control the degree of fineness of material separated from the air.

To still further reduce the force of the air returned from the receiver 26 to the charging opening of the drum through the return pipe 28, and also to separate any material from such air, an auxiliary separator 61 is provided (Figure 1) having an inlet pipe 62 of reduced size leading from the return pipe 28, said separator having an outlet to the atmosphere from the top through a pipe 63 and an outlet pipe 64 leading to either of the bins 27 to deliver any material which may be separated from the air passing through said separator.

In the modification shown in Figures 6 and 7 a series of separators 61^a, 62^a, 63^a and 64^a are connected in circuit with the pneumatic or suction means between the pipe 23 leading from the delivery side of the fan and the pipe 28, the successive separators being of increased size relative to the preceding separator whereby the force of the air is decreased at successive stages or steps,

and material delivered at said stages or steps of varying or successive degrees of fineness, a receiver or bin, shown as bags at 65 and 66 connected to the separator 61^a, 62^a, 6 being arranged at the outlets of each of the separators to receive the material separated from the air in its passage through the successive separators. The separator 61^a of the least capacity is connected by a pipe 67 with 10 the separator 62^a which is of increased capacity relative to the separator 61^a. The separator 62^a is connected by a pipe 68 with the separator 63^a of increased capacity relative to the separator 62^a, and the separator 15 63^a is connected by a pipe 69 with the separator 64^a of increased size relative to the separator 63^a. The separator 64^a corresponds to receiver 26 in the arrangement shown in Figure 1 to which the return pipe 20 28 is connected. An auxiliary separator 70, similar to the separator 61 in Figure 1, may be connected in circuit with the return pipe 28 by a pipe 71 of restricted area, the separator having an outlet to the atmosphere 25 through a pipe 72, and an outlet pipe 73 which may lead to the receiver for the separator 64^a. Either one or all of the separators, 61^a, 62^a, 63^a or 64^a may be constructed with the adjustable extension of the outlet 30 pipe shown in Figure 4 whereby to regulate the degree of fineness of the material separated from the air in its passage through said separator.

Variations may be resorted to within the 35 scope of my invention and portions of the invention may be used without others.

Having thus described my invention I claim:

1. In disintegrating apparatus, a drum 40 arranged with tubular trunnions axially at opposite ends to revolvably support the drum in horizontal position, freely moving grinding elements in the drum, and means to engage in the trunnions to reduce the size 45 of the trunnion openings, said means comprising an annular plate to engage at the outer ends of the trunnions and having an annular web arranged to extend at a re-entering angle relative to the axis of the drum.

2. In disintegrating apparatus, a cylindrical drum with freely moving grinding elements therein, said drum having hollow trunnions at opposite ends to rotatably support the drum one of which openings 55 constitutes a charging opening and the other a delivery opening, with suction means connected in circulation with said trunnions to draw air through and deliver disintegrated material from the drum, means 60 in the circulatory connection of the suction means to separate and return coarse particles of material to the drum, and means regulatably arranged in either one or both of the connections of the suction means with the drum trunnions to control either the in-

flux or efflux of air or both simultaneously to and from the drum.

3. In disintegrating apparatus, the combination of a revoluble drum with freely moving grinding elements therein and having openings at opposite ends one of which openings is adapted for the charging of material therethrough to the drum; suction means leading from one of said openings and to the other opening of the drum; a receiver 70 for the material delivered by the suction means interposed between the delivery of the suction means and the connection thereof with the drum; said connections of the suction means with the openings of the drum 75 being substantially air-tight and having openings to the atmosphere with regulable closures to control the influx of air to and the efflux of air from the drum.

4. In disintegrating apparatus, the combination of a revoluble drum having charging and delivery openings; grinding means within the drum; suction means leading from the delivery opening of the drum and to the charging opening thereof; a receiver for material delivered by the suction means interposed between the delivery of the suction means and the connection thereof with the charging opening of the drum; said connections of the suction means with the drum 80 having openings to the atmosphere with adjustable closures to regulate the size of the openings and thereby the influx and efflux of air to and from the drum; and means to feed material to be disintegrated through the charging opening of the drum constructed and arranged to maintain the charging opening shut off from the atmosphere.

5. In disintegrating apparatus, the combination of a revoluble drum having charging and delivery openings; grinding means within the drum; suction means to deliver disintegrated material from the drum; means to connect the suction means to the delivery opening of the drum having an opening to the atmosphere with an adjustable closure for regulating the area of or to close said opening; a closed receiver for material delivered by the suction means connected to the delivery of said suction means; means to connect said receiver to the charging opening of the drum having an opening therein to the atmosphere with an adjustable closure to regulate the area of said opening or to close said opening.

6. In disintegrating apparatus, the combination of a revoluble drum with grinding elements therein and having openings at opposite ends, one of which openings is adapted for feeding material to the drum and the other for delivery of disintegrated material from the drum; suction means connected to and leading from the delivery opening of the drum; a receiver for disintegrated material connected to the delivery end of the

suction means; air outlet means from said receiver leading to the feeding opening of the drum and having a substantially air-tight connection with the drum; and regulatable means in the connection of the suction means with the delivery opening of the drum to control the efflux of air from the drum.

7. In disintegrating apparatus, the combination with a revoluble drum with grinding elements therein and having charging and delivery openings axially at opposite ends, of suction means connected to and leading from the delivery opening of the drum; a receiver for disintegrated material connected to the delivery side of the suction means; a pipe leading from said receiver and having a substantially air-tight connection with the charging opening of the drum to return the air from the receiver to the drum; and a separator interposed in the connection of the suction means and receiver having an outlet connected to the charging opening of the drum to separate coarse particles of material from the air and return them to the drum for regrounding.

8. In disintegrating apparatus, the combination with a revoluble drum having charging and delivery openings axially at opposite ends, and freely moving grinding elements therein, of suction means having a substantially air-tight connection with the delivery opening to draw air with disintegrated material from the drum; a receiver to which disintegrated material is delivered by the suction means, means to feed material to the drum having a substantially air-tight connection with the charging opening of the drum; and means to control the influx of air to and the efflux of air from the drum through the action of the suction means.

9. In pulverizing apparatus, the combination with a revoluble drum having openings axially at opposite ends, of means in substantially air-tight connection with one of said openings to feed material therethrough to the drum; and suction means having a substantially air-tight connection with the other opening to draw and deliver pulverized material from the drum, said connection of the suction means with the drum having an opening to the atmosphere with a regulable closure for controlling the suction from the drum.

10. In pulverizing apparatus, the combination with a revoluble tubular drum with freely moving grinding elements therein and having openings axially at opposite ends; means having a substantially air-tight connection with one of the openings to feed material to be pulverized to the drum through said opening; and a suction fan connected to the other opening to draw and deliver pulverized material from the drum; said connections of the feeding and suction

fan with the drum having openings with regulable closures to control the influx of air to and efflux of air from the drum.

11. In pulverizing apparatus, the combination of a revoluble tubular drum with freely moving grinding elements therein and having charging and delivery openings axially at opposite ends; suction means having a substantially air-tight connection with and leading from the delivery opening of the drum; means having a substantially air-tight connection with the charging opening of the drum to feed material therethrough to the drum; and means arranged in the connection of the feeding and suction means with the drum for feeding the grinding elements thereto.

12. In pulverizing apparatus, the combination with a revoluble tubular drum with freely moving grinding elements therein and having charging and delivery openings at opposite ends; of a receptacle at each end of and in communication with the drum openings with means to maintain a substantially air-tight connection between the drum and receptacles; means to feed material to the drum through the receptacle connected to the charging opening and maintain said receptacle shut off from the atmosphere; a suction fan connected to the receptacle at the delivery end of the drum to draw air with pulverized material from the drum; a receiver for the air pulverized material connected to the delivery side of the fan and arranged to separate pulverized material from the air; an air return pipe leading from the receiver to the receptacle connected to the charging opening of the drum; and regulatable means arranged in the receptacles to control the influx of air to and efflux of air from the drum.

13. In pulverizing apparatus, the combination with a revoluble tubular drum, with means therein for grinding material and having hollow supporting trunnions to serve as charging and delivery openings at opposite ends with the inner walls arranged at an angle to re-enter material into the drum entering said trunnions, of a closed receptacle at each end of the drum in communication with the trunnions with which the drum has a sliding joint and substantially air-tight connection; means to deliver material to the drum through the receptacle connected to the charging trunnion; a suction fan connected to the receptacle at the delivery end of the drum to draw air and deliver pulverized material from the drum; a receiver for the pulverized material connected to the delivery side of the fan; an air return pipe from said receiver to the receptacle at the charging end of the drum; and a separator interposed between the delivery side of the fan and receiver and having an outlet connected to the charging opening of the drum.

to return unpulverized material to the drum.

14. In pulverizing apparatus, a drum having grinding means therein and charging and delivery openings; pneumatic means connected in circuit with charging and delivery openings of said drum to deliver material from the drum; a separator interposed in said pneumatic means to separate material from the air delivered by the pneumatic means, said separator being arranged with adjustable means to adapt the same to separate material of different degrees of fineness from the air and have connection with the drum for returning coarse material to the drum; and a receiver connected in the pneumatic means to receive material from said separating means.

15. In disintegrating apparatus, the combination with a drum arranged with means therein to grind material; and having charging and delivery openings, of pneumatic means in circulation with the charging and delivery openings of the drum to deliver disintegrated material from the drum; and means connected in circulation with the pneumatic means at the delivery side of the pneumatic means to separate material of variable degrees of fineness from the air delivered by the pneumatic means, comprising a chamber into which the pneumatic means delivers at the side, an outlet pipe leading from the top of the chamber in a line transverse to the delivery of the air into the chamber, an auxiliary pipe having a telescoping connection with the outlet pipe and adapted to be extended variable distances into the chamber, and an outlet leading from the bottom of said chamber to the charging opening of the drum for the separated material.

16. In disintegrating apparatus, the combination with a drum arranged with means therein to grind material; and having charging and delivery openings, of pneumatic means connected in circulation with the charging and delivery openings of the drum to deliver disintegrated material from the drum; and means connected in circulation with the pneumatic means at the delivery side of the pneumatic means to separate material of variable degrees of coarseness from the air delivered by the pneumatic means, comprising a cylindrical casing having a chamber therein with the wall converging toward the bottom and having an outlet at the apex of said converging wall, the connection of the pneumatic means with said casing being tangential with the peripheral wall thereof, an air outlet pipe leading from the top of said casing, and an auxiliary pipe having telescoping connection with the outlet pipe and adapted to be extended variable distances into the casing chamber.

17. In disintegrating apparatus, a revolvable drum in which to disintegrate material

having charging and delivery openings, pneumatic means connected in circulation with the drum including a fan to deliver pulverulent material from the drum, and regulatable means to variably open the charging end of the drum and the intake of the fan to the atmosphere operative to regulate the drawing of air with pulverulent material from the drum by the fan without impairing the intake of air to or delivery and lift of the air from the fan.

18. In disintegrating apparatus, a revolvable drum in which to disintegrate material having charging and delivery openings, pneumatic means connected in circulation with the drum including a fan to deliver pulverulent material from the drum, means interposed in the pneumatic means to separate pulverulent material from the air delivered by the fan, openings to the atmosphere at the charging end of the drum and intake to the fan, and regulatable means for said openings to vary the area of the opening thereof to the atmosphere to regulate the influx of air to the drum and efflux of air with pulverized material of variable fineness from the drum while maintaining the intake of air to the fan as well as the delivery and lift of air from the fan constant.

19. In pulverizing apparatus, a drum in which to disintegrate material having charging and delivery openings at opposite ends, means to feed material through the charging opening of the drum, pneumatic means connected in circuit with the drum to deliver material from the drum, a separator interposed in said pneumatic means to effect a primary separation of material from the air drawn from the drum by the pneumatic means, said separator being arranged with adjustable means to separate material of variable degrees of fineness from the air and having connection with the drum for returning to the drum material separated from the air in said separator, and a collecting separator connected in the pneumatic means to receive the air from the primary separator.

20. In pulverizing apparatus, a revolvable drum, in which to disintegrate material having charging and delivery openings at opposite ends, means to feed material to the drum through the charging opening, pneumatic means connected in circuit with the drum to draw air with disintegrated material from the drum through the delivery opening, a separator in said pneumatic means to effect a primary separation of material from the air drawn from the drum by the pneumatic means, said separator having an outlet pipe, a sleeve slidable longitudinally of said outlet pipe and adjustable variable distances into the separator and operative to effect separation of material of variable degrees of fineness from the air in its passage through said separator, and the separator having a

connection with the drum for returning to the drum material separated from the air in said separator, and a collecting separator connected in the pneumatic means to receive air from the primary separator.

21. In disintegrating apparatus, a revolvable drum in which to disintegrate material having charging and delivery openings, pneumatic means connected to the delivery opening of said drum to deliver material from the drum, a separator interposed in said pneumatic means to separate material from the air drawn from the drum by the pneumatic means including a chamber hav-

ing an inlet for the dust laden air from the drum, a connection with the drum to return material to the drum separated from the air in its passage through said chamber, an outlet pipe for the air, and a sleeve telescopic relative to the outlet pipe and adjustable to variable extent into the chamber to effect separation of material of variable degrees of fineness from the air in its passage through the chamber.

Signed at the city of New York, in the county of New York and State of New York, this 2nd day of October, 1922.

JOSEPH E. KENNEDY.
